UNITED STATES PATENT OFFICE.

MILTON M. ADLER, OF NEWARK, NEW JERSEY.

PYROTECHNICAL DEVICE.

Application filed April 17, 1923. Serial No. 632,664.

To all whom it may concern:

Be it known that I, MILTON M. ADLER, a citizen of the United States, residing at Newark, in the county of Essex and State 5 of New Jersey, have invented certain new and useful Improvements in Pyrotechnical Devices; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 This invention relates to improvements in pyrotechnical devices in the nature of a detonating fire-work or fire-cracker of the general type or kind shown and described in my prior United States Letters Patent No. 20 1,441,551, dated January 9th, 1923.

This invention has for its principal object to provide a detonating fire-work or fire-cracker which is safe to handle, which will not fly apart when set off so as to endanger 25 the eyes or person of the user, or entail risk of igniting fires, and which is constructed to produce, when set off, a series or intermittent succession of detonations, rendering the same of pleasing and interesting effect, 30 and providing a fire-work or fire-cracker which will operate for a comparatively long time after it is ignited.

Other objects of this invention, not at 35 this time more particularly enumerated, will be clearly understood from the following detailed description of the same.

With the various objects of this invention in view, the same consists, primarily, in the novel detonating fire-work or fire-cracker 40 hereinafter set forth; and, the invention consists, furthermore, in the novel arrangements and combinations of the several devices and parts, as well as in the details of the construction of the same, all of which 45 will be hereinafter more fully described in the following specification, and then finally embodied in the claim appended thereto.

The invention is clearly illustrated in the accompanying drawings, in which:—

50 Figure 1 is a perspective view of the complete fire-work or fire-cracker, made according to and embodying the principles of the present invention; Figure 2 is a vertical cross section through the same; Figure 3 is 55 a perspective view of the detonating element removed from the casing; Figure 4 is a ver-

tical cross section of a modified form of the detonating element; Figure 5 is a vertical cross section of the detonating element showing a modified arrangement of the attached 60 end of the fuse connected therewith; and Figure 6 is a similar view showing a modified form of the detonating element.

Similar characters of reference are employed in all of the hereinabove described 65 views, to indicate corresponding parts.

Referring now to said drawings, the reference character 1 indicates an outer casing or box, the upper wall of which is provided with an opening 2. Said casing or box 1 is 70 provided at its opposite ends with end-flaps 3 provided with tuck-flaps 4, whereby the ends of the casing or box are normally closed. Provided in said end-flaps 3, or at other points in the sides of the complete 75 casing or box, are a plurality of ventilating perforations 5, which permit access of air into the interior chamber 6 provided by the casing or box. The said casing or box is preferably made of comparatively heavy 80 paper or light card-board, or of any other suitable material.

The reference character 7 indicates a solid disc-like body or lozenge of pyrotechnical composition adapted to produce 85 intermittent detonations when ignited. A composition suitable for the production of the disc-like body or lozenge 7 comprises a mixture of gum-arabic, carbonate of magnesium, white phosphorus, red ocher and 90 potassium chlorate. In this composition the phosphorus and potassium chlorate are the combustible and detonating or explosive elements which are, in the mixture, separated by the carbonate of magnesium and the 95 inert filler formed by the red ocher, the gum arabic being the binder. When this composition is mixed together and dried in disc-like or lozenge form and then ignited the combustion thereof will be comparatively slow, and will be accompanied by intermittent detonations as the particles of potassium chlorate are ignited. It will, of course, be understood that I do not limit myself necessarily to the use of the particular detonating composition above described, 100 since I may employ for the purpose any other pyrotechnical compound known to those skilled in the art which is adapted to produce when ignited a slow combustion accompanied by intermittent explosions or detonations. After the disc-like body or loz-

- 2
- enge 7 of pyrotechnical composition is formed and before the same hardens I attach thereto a fuse-element 8, one end of which may be imbedded in the disc-like body or lozenge 7 as shown in Figures 2, 3 and 4. If desired the disc-like body or lozenge 7 may be wrapped in an adhering covering of thin paper or the like 9, as shown in Figures 2 and 3, whereby undue disruption of the body or lozenge 7 is prevented during the combustion thereof. It will be understood, however, that said covering of paper or the like 9 may be omitted if desired, as shown in Figure 4. Instead of imbedding the end of the fuse-element 8 in the body or lozenge 7 as heretofore mentioned, I may wrap the said body or lozenge in the covering of paper or the like 9, and then attach one end of the fuse-element 8 to the exterior surface thereof by means of an adhesive 10, such as dextrine or other suitable gum, as shown in Figure 5; or I may omit the paper covering 9, and attach the fuse-element 8 by means of the adhesive 10 directly to the surface of the body or lozenge 7, as shown in Figure 6; and in fact I may attach said fuse-element 8 operatively to the body or lozenge 7 in any other manner found convenient or desirable.
- After the combustible detonating body or lozenge 7 with the fuse-element 8 attached thereto is prepared, the same is inserted in the casing or box 1, with the free end of said fuse-element 8 projecting outwardly through the top opening 2, and then the side flaps 3 of the casing or box are closed, whereupon the device is ready for use. In operation, the free end of said fuse-element 8 is ignited and burns down until the combustion thereof is communicated to the body or lozenge 7, whereupon the latter burns and gives off the intermittent detonations characteristic thereto, and which will continue for a comparatively long time. Air to support the combustion of the body or lozenge 7 will circulate through the interior 6 of the box or casing 1 finding access thereto through the perforations 5 provided in the sides of the casing and through the opening 2 in the top thereof. The detonating body or lozenge 7 tends to disrupt more or less during the combustion thereof, but nevertheless the disrupted or separated particles breaking off from the body or lozenge under the explosive effects accompanying combustion cannot fly about promiscuously or escape from the enclosing casing. It will therefore be quite evident that the device is unusually safe for children's amusement since there is little danger of scattering particles of fire or smoldering fragments burning the child, igniting its clothing, or objects in the vicinity wherein the device is set off.
- I am aware that some changes may be made in the arrangements and combinations of the parts making up the device, as well as in the details of the construction and composition of the same, without departing from the scope of this invention as set forth above and as defined in the appended claim. Hence, I do not limit myself to the exact arrangements and combinations of the various devices and parts, as described in the foregoing specification, nor do I confine myself to the exact details of the construction of the said parts as illustrated in the accompanying drawings.
- I claim:
- A pyrotechnical device, comprising a casing, adapted to provide a hollow enclosed interior, a lozenge of detonating pyrotechnical composition loosely disposed within said casing, adapted to produce intermittent detonations when ignited a fuse-element having one end affixed to said lozenge of pyrotechnical composition, said casing having an opening in the top wall thereof through which the free end of said fuse-element may project exteriorly from said casing, and the side walls of said casing having ventilating perforations to admit air into the interior of said casing.
- In testimony, that I claim the invention set forth above I have hereunto set my hand this 20th day of March, 1923.
- MILTON M. ADLER.
